ORNAMENTAL HOLLOW METAL BALL

Application filed May 11, 1928. Serial No. 277,015.

This invention relates to ornamental hollow balls or spheres such as are used in jewelry as necklace beads, pendants and heads of hatpins and the like.

5 These hollow balls have heretofore been made from a flat blank stamped from a sheet of metal and embodying a plurality of radiating leaves integrally joined at their adjacent inner ends, and each having the 10 outline of a section of the ball or sphere to be made. The leaves of the blank have then been suitably brought together and given the necessary longitudinal and transverse contour or shape to produce the finished 15 article, the side edges of the leaves being in contiguous relation, and a space being left between the adjacent normally outer or free ends of the leaves to form a hole and provide for stringing the balls or 20 threading a string therethrough. However, there is likely to be a slight space or opening between the edges of adjacent leaves at the point where the normally outer or free ends of the latter are brought together, and 25 it often happens that in stringing these balls, the fine thread or wire becomes caught in the space or opening between the adjacent sections. In an endeavor to overcome this difficulty, it has been proposed to solder 30 the leaves or sections where the free ends thereof meet, or to solder a separate ring or eyelet on the meeting free ends of the sections or leaves. However, for various reasons, both proposed methods have proven 35 unsatisfactory, particularly because of difficulty in carrying the same out and preserving a neat appearance.

The primary object of the present invention, therefore, is to provide an improved 40 ornamental hollow metal ball and method of making the same, whereby the mentioned difficulty is most readily and effectively overcome. I accomplish this object by forming an unbroken or continuous ring or eyelet 45 on the normally free or outer end of one of the leaves or sections of the blank, and by forming notches in the normally free or outer ends of the remaining sections for accommodating the adjacent portions of 50 said integral eyelet or ring when the sec-

tions are shaped and brought together to produce the completed or finished article.

The invention consists in the novel article and method hereinafter more fully described, shown in the accompanying drawing 55 and claimed.

In the drawing:—

Figure 1 is a plan view of the improved blank from which the present ornamental hollow metal ball is formed;

Figure 2 is a plan view of the complete ball; and

Figure 3 is an enlarged section on line 3—3 of Figure 2.

Referring more in detail to the drawing, 65 the present invention contemplates the production of a flat metal blank of the general form shown in Figure 1 and embodying a plurality of radiating leaves or sections 5 integrally joined at their adjacent inner ends 70 as generally indicated at 6, and each having the outline of a section of the hollow article to be formed. In forming the blank, a piece of sheet metal is preferably placed upon a die whose surface has been supplied 75 with a desired design engraved to a proper depth, and this piece of sheet metal is struck until portions of the surface are desirably raised and ornamented. The ornamented part is then cut or punched from the sheet 80 to form the blank of Figure 1, portions of the metal being removed as indicated at 7 so that the leaves 5 are of open work formation as clearly illustrated, and so that a continuous or unbroken integral eyelet 8 is 85 formed at the juncture of the adjacent inner ends of the leaves 5, with an integral continuous or projecting eyelet 9 formed on the outer end of one of the leaves 5, and with suitable notches or recesses 10 formed in the outer ends of the remaining leaves 5. The leaves or sections 5 are then suitably shaped into a hollow sphere as clearly shown in Figures 2 and 3, in a method and by means well known in the art. When the leaves 90 are thus shaped, the eyelet 9 seats in the recesses or notches 10 so as to provide a neat joint where the normally free or outer ends of the leaves are brought together, and to provide a durable eyelet at this point 95 100

through which a string may be threaded without danger of being caught by passing between the adjacent edges of the leaves at this point. The opposite poles of the sphere or ball are thus provided with unbroken or continuous integral eyelets in a simple and efficient manner so as to insure an entirely neat and satisfactory article whose manufacture involves no soldering or attachment of separate rings or eyelets.

5 It is obvious that the device may be used to produce various articles of jewelry with equal advantage, and the ball may readily be formed of spheroidal or other shapes.

10 15 From the foregoing description it is believed that the article and method of forming the same, as well as the advantages incident thereto, will be readily understood and appreciated by those skilled in the art.

20 25 Minor changes may be made without departing from the spirit and scope of the invention as claimed.

What I claim as new is:

1. As an improved article of manufacture, an ornamental hollow metal ball composed of a plurality of joined radial leaves and having an integral continuous eyelet where the ends of the leaves meet at each pole of the ball.

30 35 2. As an improved article of manufacture, an ornamental hollow metal ball composed of a plurality of radial leaves having adjacent ends integrally joined at one pole of the ball, and a projecting integral eyelet on the end of one leaf at the opposite pole of the ball, the ends of the remaining leaves at said opposite pole of the ball having recesses in which said eyelet is seated.

40 45 3. As an improved article of manufacture, an ornamental hollow metal ball composed of a plurality of radial leaves having adjacent ends integrally joined at one pole of the ball, and a projecting integral eyelet on the end of one leaf at the opposite pole of the ball, the ends of the remaining leaves at said opposite pole of the ball having recesses in which said eyelet is seated, said ball having a further integral eyelet where the ends of the leaves are integrally joined at the first-named pole of the ball.

In testimony whereof I affix my signature.

CHARLES H. FULLER.
